UNITED STATES PATENT OFFICE.

CHRESTEN KNUDSEN, OF PORTLAND, MAINE.

SAFETY-HOOK.

1,324,676.

Specification of Letters Patent. Patented Dec. 9, 1919.

Application filed July 6, 1918. Serial No. 243,563.

To all whom it may concern:

Be it known that I, CHRESTEN KNUDSEN, a citizen of the United States, residing at Portland, in the county of Cumberland and 5 State of Maine, have invented new and useful Improvements in Safety-Hooks, of which the following is a specification.

This invention relates to safety hooks especially designed for cargo hoisting and 10 lowering, the object in view being to provide a safe and reliable hook for the purpose stated, which is simple in construction, economical in manufacture, and which may be used with perfect safety in the raising 15 and lowering of heavy articles, the hook being specially designed for marine use, but being, of course, valuable in other connections and uses which will suggest themselves.

With the above and other objects in view, 20 the invention consists in the construction, combination and arrangement of parts, as herein described, illustrated and claimed.

In the accompanying drawings:

Figure 1 is a side elevation partly in 25 section of the improved hook, showing the latch or tongue in its closed position.

Fig. 2 is a similar view showing the open position of the latch or tongue.

Fig. 3 is a section on the line 3—3 of 30 Fig. 1, to show the spring-pressed pin housed in the latch, and arranged to be held under yielding pressure against the cam-face of the lug on the hook-body to prevent casual opening movement of the latch.

Referring to the drawings, 1 designates 35 the body of the hook, which is so shaped that it may be drop forged from steel or any suitable metal, thereby rendering the same reliable for heavy duty work. As shown,

the body 1 is provided with a rope or cable 40 receiving eye 2. The cable attaching means, however, may be of any shape or construction, according to the particular use to which the hook is to be put. The bill or

45 point 3 of the hook is formed in opposite sides of the inner face thereof with notches or recesses 4 embodying two substantially straight shoulders or walls 5 and 6 arranged at an angle to each other to receive and support against lateral and outward swinging movement, the free bifurcated end of a latch or tongue 7. The hook is further provided adjacent to the junction between the body 1 and the attaching means 2 with a

50 projecting lug 8, having a cam face 9, the purpose of which will appear.

The tongue or latch 7 is connected to the lug 8 by means of a pivot 10 and the heel end of the latch is formed with a rounded bearing face 11 and concentric with the pivot 10 and adapted to bear against and cooperate with an opposed shoulder 12 as shown in Figs. 1 and 2, thus removing most of the strain from the pivot 10 when any pressure is brought to bear against the inner or under side of the latch which would have the effect of pressing the free end of the latch outward. The latch is bifurcated or slotted adjacent to its pivot end as shown at 13 to form a recess for the lug 8 and the latch is also formed with a central longitudinal bore or socket 14 in which is placed a compression spring 15, the inner end of which is supported by the inner end wall 16 of the socket or recess 14. A pin 17 is inserted through the convolutions of the spring 15 and is provided with a rounded head or shoe 18 which rides against the cam face 9 of the lug 8 in the back and forth pivotal movements of the latch or tongue 7 and thereby effectively prevents accidental movement of the latch from the closed position shown in Figs. 1 and 3 to the open position shown in Fig. 2. It will also be observed that outward movement of the free end of the latch 7 beyond the fully closed position of the latch is prevented by the strong bearing of said end against the inner side of the bill 3 of the hook, while sidewise movement of said free end, 50 when the latch is closed, is precluded by the straddling of the bill portion between the recesses 4 by the bifurcated end of the latch. The spring 15 is completely housed within the socket in the latch member and 55 the head 18 of the pin 17 takes the wear, thereby protecting the spring and greatly increasing the life thereof. A new pin 17 may be substituted for an old pin which has become worn through sliding contact with 60 the cam face 9 of the lug 8. The latch or tongue 7 is preferably formed of malleable iron or other metal and as the body 1 will ordinarily be formed of a drop steel forging, an especially tough, durable and reliable safety hook is produced.

I claim:

1. A safety hook comprising a hook-shaped body and a movable latch; the body having attaching means, a lug at the inner side of the body adjacent to said attaching means and on which is a cam face opposite

the bill of the body, shoulders at opposite sides of said lug, and recesses in opposite sides of the inner side portion of the bill, and the latch being pivoted to the body lug 5 eccentrically to the cam face thereof and having a rounded inner end to bear against the shoulder of the body and also having a bifurcated free end to engage the recessed inner side of the bill and bear outwardly 10 against the bill, and a spring-pressed pin housed in the latch and arranged when the latch tends to open, to exert yielding pressure against the cam face of the lug on the body.

15 2. A safety hook comprising a hook-shaped body and a movable latch; the body

having attaching means and a portion at the inner side of the body adjacent to said attaching means and on which is a cam face opposite the bill of the body, and the latch being pivoted to the said body portion eccentrically to the cam face thereof and arranged when closed to bear outwardly against the inner side of the bill of the body, and spring-pressed means carried by the 20 latch and arranged when the latch tends to swing toward the open position, to exert yielding pressure against the cam face of the said body portion.

In testimony whereof I affix my signature. 25

CHRESTEN KNUDSEN.
